UNITED STATES PATENT OFFICE

HARRISON L. SKILLMAN, OF YOUNGSTOWN, OHIO.

COMBINED EAVES-TROUGH AND DOWN-SPOUT CONSTRUCTION.

1,226,712.

Specification of Letters Patent. Patented May 22, 1917.

Application filed February 25, 1916. Serial No. 80,420.

To all whom it may concern:

Be it known that I, HARRISON L. SKILLMAN, a citizen of the United States, residing at Youngstown, in the county of Mahoning and State of Ohio, have invented certain new and useful Improvements in Combined Eaves-Trough and Down-Spout Construction, of which the following is a specification.

This invention relates to the general subject of roofing, and has particular reference to a novel and improved eaves-trough and down-spout construction.

A primary object of the invention is to provide an eaves-trough that will overhang the edge of the roof and lie in a well-protected position beneath the eaves to thereby effectually exclude all foreign and obstructing matter, and also provide an adjustable down-spout connection for carrying the water away from the trough.

Another object of the invention is to provide a strong and substantial mounting for supporting the trough beneath the eaves of the roof, which will permit of the same being readily removed for painting or repairs, while at the same time providing a guard edge which will readily deflect obstructions such as snow and ice upwardly and beyond the edge of the roof and clear of the trough entrance.

A further object of the invention is to provide a simple and practical construction, whereby the trough and down spout may be adjustably connected or coupled so that the latter may be adjusted from a perpendicular position to any desired angle or slant required to reach the ground.

With the above and other objects in view which will more readily appear as the nature of the invention is better understood, the same consists in the novel construction, combination and arrangement of parts hereinafter more fully described illustrated and claimed.

A preferred and practical embodiment of the present invention is illustrated in the accompanying drawings, in which—

Figure 1 is a perspective view showing the application of the invention, the down-spout being shown in full lines in a perpendicular position.

Fig. 2 is a vertical sectional view of the construction shown in Fig. 1, the dotted lines indicating the slant or angle at which the down-spout may be set.

Similar reference characters designate corresponding parts throughout the several figures of the drawings.

In carrying the present invention into effect, it is proposed to employ a suitable metallic trough section 1, which may be of any desired cross-sectional shape, but preferably of the angular type shown, which includes a flat bottom 2 and the up-standing side walls 3 and 4. As illustrated, the wall 3 is provided at its upper edge with an angled attaching flange 5 which may be held by suitable fastening elements 6 to the underside of the roof R. The opposite wall 4 is provided at its upper edge with an inturned attaching flange 7, adapted to fit in the recess 8 of a trough supporting bar 9.

This trough supporting bar extends throughout the length of the roof at the edge thereof, and is provided with an upwardly directed deflecting face 10, and is further provided with the offset spaced attaching feet 11 for securing the same to the upper surface of the roof. The body portion of this bar having the recess 8 in its upper edge terminates short of the bottom edges of the attaching feet 11 to thereby provide a clearance space or slot 12 which constitutes an entrance for the trough section 1. That is to say, this bar, when secured in position along the edge of the roof, is spaced above the same so as to provide for the passage of water directly underneath into the trough section 1, which as shown, lies in an almost wholly concealed position beneath the eaves of the roof.

From the foregoing, it will be apparent that the entire trough section is supported at its outer edge by means of the supporting bar 9, whose recess 8 flushly receives the inturned and supporting flange 7 of the outer side 4 of the trough section 1. This attaching flange is preferably secured to the supporting bar 9 by means of suitable detachable fastening elements E, so that when desired the trough may be readily detached from the bar for painting, repairs or the like. When secured in the recess 8, the upper face of the flange 7 cooperates with the inclined face 10 of the bar to provide a continuous inclined deflecting surface which will direct solid matter sliding down the roof upwardly and over the edge thereof thus keeping the interior of the trough free from obstructions.

The invention involves a combined eaves-trough and down-spout construction, and embodies in connection with the eaves-trough a down-spout member 13, attaching member 14 and an intermediate connecting pipe 15. As will be observed from the drawings, the cross-sectional shape of the attaching member 14 corresponds to that of the trough section 1, so that the said 5 attaching member may telescopically engage with the end of the trough. This attaching member therefore, includes the side wall portions 16 and 17, the former having a substantially hooked shaped flange 15 portion 18 for fitting over the attaching flange 7 of the trough section, while the opposite wall 17 engages with the wall 3 of the trough section at one side of the outlet A thereof. Disposed at right angles 10 to the walls 16 and 17 of the attaching member, are the upstanding walls 19 and 20, the latter forming an end closure for the trough at the edge of the roof, and both these walls being offset to provide a 15 spout end S which fits into the connecting pipe section 15.

The connecting pipe section above referred to is pivotally supported at one end on the spout portion of the attaching member by the pivot elements 21, in such a way 20 that the same will be adjustably connected therewith without impairing the efficiency of the joint, while the other or outlet end has swiveled thereto by means of the pivots 25 22 the down-spout member 13. Thus, as shown, the outlet end B of the section 15 projects into the down-spout member 13 to such an extent that the latter has a wide range of movement on the pivots 22, 30 whereby it may be adjusted to any angle 35 to reach the ground or waste connection. That is to say, if the eaves of the roof project a considerable distance from the sides of the house, the adjustable connections between the down-spout member and the 40 trough make it possible for the former to be set at any required angle, such for instance, as indicated by the dotted lines in Fig. 2, and still maintain an effective 45 coupling or joint.

Without further description, it is thought that the many features and advantages of the present invention will be readily ap-

parent, and it will also be understood that various changes in the form, proportion, 55 and minor details of construction may be resorted to without departing from the spirit of the invention or scope of the appended claims.

I claim:

1. An eaves trough construction including in combination with the roof eaves, a supporting bar having a flange receiving seat and a plurality of attaching feet, said feet lying in a plane beneath the body of the bar to space the latter from and above the edge of the roof, an eaves trough having at its outer upper edge an angular attaching flange adapted to fit in said seat of the supporting bar, and an outlet member carried by said eaves trough.

2. An eaves-trough construction including in combination with the roof eaves, a supporting bar having an upwardly directed deflecting face and a rabbeted eaves-trough flange receiving seat, and also having a plurality of attaching feet, said feet lying in a plane beneath the body of the bar to space the latter above the edge of the trough, an eaves-trough having an attaching flange filling in said rabbeted seat of the supporting bar, and an outlet member telescopically fitting over one end of the eaves-trough.

3. An eaves-trough construction including in combination with the roof eaves, a supporting bar secured to said roof eaves and spaced above the upper edge thereof, an eaves trough having opposite side walls one of which has a flange for engaging the 85 said supporting bar, and the other of which may be secured to the under side of the roof eaves, and said latter wall having one end thereof cut away to provide an exit for the trough, and an L-shaped outlet member 90 telescopically engaging the end of said eaves-trough and having a flange for engaging over the flange of the trough which engages the supporting bar.

In testimony whereof I hereunto affix my 100 signature in the presence of two witnesses.

HARRISON L. SKILLMAN.
